UNITED STATES PATENT OFFICE.

CARLO MERLI AND GIUSEPPE BERTOLINI, OF NEW YORK, N. Y.; SAID BERTOLINI
ASSIGNOR OF HIS ENTIRE RIGHT TO VICTOR KLEINBERG, SALVATORE MANGIA-
PANE, AND FRANK FUMO, ALL OF NEW YORK, N. Y.

KNITTING MACHINE.

Application filed February 8, 1921. Serial No. 443,454.

To all whom it may concern:

Be it known that we, CARLO MERLI and GIUSEPPE BERTOLINI, citizens of Italy, residing at New York, in the county of New York and State of New York, have invented new and useful Improvements in Knitting Machines, of which the following is a specification.

This invention relates to machines for tying articles and has for an object the provision of a machine which is especially designed for tying or knitting a cord or the like around meats, previously stuffed within a skin or casing the machine being designed 10 for use in connection with an improved stuffing machine for which an application has been filed by us of even date herewith.

Another object of the invention is the provision of a machine as above specified, in which the meat or other article is fed 20 through a cylinder, the machine being operated during such feeding, so that the cord will be wrapped and looped about the article in a manner to provide a series of relatively tightly drawn interwoven convolutions and loops and thus maintain the article in an attractive and sanitary condition.

Another object is the provision of a knitting machine which includes a plurality of 30 separate units, preferably of different sizes to accommodate different size articles, the said units being operated simultaneously or independently, the character of the article for which the machine is especially designed 35 varying in size, so that the said articles may be graded and fed through their proper unit.

With the above and other objects in view, the invention further includes the following 40 novel features and details of construction, to be hereinafter more fully described, illustrated in the accompanying drawings and pointed out in the appended claim.

In the drawings:—

Figure 1 is a side elevation of a knitting machine embodying the present invention.

Figure 2 is a top plan view of the same.

Figure 3 is a sectional view on the line 3—3 of Figure 1.

Figure 4 is a fragmentary end view of the

machine, the view being on an enlarged scale.

Figure 5 is a vertical sectional view through the subject matter of Figure 4.

Figure 6 is a detail elevation of one of the 55 revolving cylinders.

Figure 7 is an enlarged fragmentary view showing the manner in which the cord or thread is looped or interwoven about the article.

Figure 8 is an enlarged elevation of the cord container and cord tensioning device.

Figure 9 is a fragmentary plan view of the tensioning device.

Referring in detail to the drawings, 65 wherein like characters of reference denote corresponding parts, the machine as illustrated includes a table 10, which may be supported in any suitable manner, as upon legs 11.

Rising from the top 12 of the table is a plurality of vertically disposed rods or standards 13, which have their upper ends secured to a supporting plate 14, the latter being provided with spaced openings 15. 75 Positioned within each of the openings 15 is a cylinder 16, the latter being provided at its lower end with a reduced portion 17 and a shoulder 18, the former being received within the opening 15 of the table top, while the latter rests upon the upper face of the said top, so that the cylinder 16 is rotatably mounted within the opening 15.

As shown in the drawings a number of 85 these cylinders are provided, the said cylinders varying in size, the purpose being to provide for tying articles of different sizes. This is essential in a machine used for the purpose for which the present machine is especially designed, that is, in tying certain 90 cuts of meat previously stuffed within a skin or casing, the said cuts not being of a uniform size.

Spaced above the supporting plate 14 by means of spacing rods 19 is a plurality of 95 relatively small bearing plates 20, which are provided with openings 21 for the reception of the cylinders 16, the said plates surrounding said cylinders and having secured there to a stationary cam sleeve 22, one of these 100

2
sleeves also surrounding each of the cylinders 16.

- Operatively mounted in each of the cylinders 16 is a plurality of knitting needles 23, 5 the number of these needles being regulated in accordance with the diameter or size of the cylinders 16. As shown in the drawings the number of these needles range from four to seven, although this number may vary 10 in accordance with the closeness which it is desired that the article be wrapped. The needles 23 operate in longitudinally disposed slots 24 provided in the outer periphery of the cylinders 16, the said needles being of 15 the usual type employed in connection with knitting machines, that is, they include a hook 25, a pivoted latch 26 and a butt 27, provided in the shank of the needle opposite the hook end. The stationary cam sleeve 22 is provided 20 with a cam slot 28 which receives the butt portions 27 of the needles, so that when the cylinder 16 is rotated, in a manner to be hereinafter described, these needles will be moved longitudinally of their guide slots 24. 25 For the purpose of rotating the cylinders 16, each of said cylinders is provided with gear teeth 29, the teeth of each adjacent cylinder being engaged by a gear 30, which is mounted upon a stub shaft 31. The teeth 30 of one of the cylinders 16 is engaged by a gear 32, which is shown as carried by a vertically disposed shaft 33. This shaft also carries a beveled pinion 34 which is engaged by a pinion 35 carried by a shaft 36, 35 upon which is mounted fast and loose pulleys 37, by means of which power may be applied to the machine. The shafts 33 and 36 are mounted in suitable bearings provided in a standard 38 rising from the table top 40 12. The gears 30 are loosely mounted upon the stub shafts 31 and when these gears are in position, each of the cylinders 16 may be simultaneously rotated. However, if it is desired to cut out the operation of some of 45 the cylinders 16, certain of the gears 30 may be removed from the shafts 31. The machine thus provides a plurality of separate units, which may be simultaneously or independently operated. 50 Rising from the bearing plates 20 adjacent each of the cylinders 16 is a vertically disposed arm 39 which supports a container 40, the latter being adapted to contain a cord or other implement for wrapping or 55 tying the article. This cord passes through a tensioning device which includes a support 41 extending from the container 40 and a spring arm 42, the latter being provided with a cord receiving slot 43. The cord 60 passes from the container downward through this slot between the spring plate 42 and the support 41, tension being regulated by means of a set screw 44. The cord passes from the tensioning device to a guide finger 45 one 65 of which is secured to each of the stationary

cam sleeves 22, the said finger being arranged to properly position the cord for engagement by one of the needles 23.

In the operation of the machine, power is applied to rotate the cylinders 16 and one 70 end of the article is inserted within the top of one or more of the said cylinders. Rotation of these cylinders will cause the cord to be wrapped about the article in spiral formation, the needles on their downward movement 75 engaging the cord within their hooks 25 and drawing the said cord downward within notches 46 provided in the upper edge of the cylinders 16. During this downward movement, the latches 26 of the needles will 80 be closed by the convolution of the cord immediately below the one in which the loops have just been formed and will draw the cord through these loops in the manner illustrated in Figure 7 and provide a knitted or 85 interwoven wrapping for the article. As soon as one article has been wrapped or tied, another may be fed immediately through the guide, so that a series of connected articles may be provided as is also shown in Figure 90 7. The table top 12 is provided below each of the units with openings 47 and the articles may thus be continuously fed through the machine and afterward separated as desired. 95

The invention is susceptible of various changes in its form, proportions and minor details of construction and the right is herein reserved to make such changes as properly fall within the scope of the appended claim. 100

Having described the invention what is claimed is:—

A knitting machine embodying a table, a plurality of horizontally arranged supporting plates spaced above the table and having 105 openings therein, cylinders varying in diameter and having their lower ends mounted for rotation in said openings, needles operatively mounted about the cylinders, a stationary sleeve surrounding each cylinder and 110 having a cam groove therein, the walls of which engage the needles, an annular flange extending around the bottom of said sleeve, and spaced rods connecting the plate and sleeve flange for supporting the sleeve 115 spaced about the cylinder supporting plate, whereby said sleeves will provide a bearing for the cylinders, a gear train connecting the cylinders, said train including gears surrounding the cylinders and positioned between the supporting plate and sleeve flange, and confined within the spaced rods, means whereby the gears may be operated to rotate the cylinders, and means whereby cord may be supplied to the needles. 120

In testimony whereof we affix our signatures.

CARLO MERLI.
GIUSEPPE BERTOLINI.
